UNITED STATES PATENT OFFICE.

HENRY C. ANDERSON, OF ATHENS, GEORGIA.

DESIGN FOR A BOTTLE.

52,423.

Specification for Design. Patented Sept. 17, 1918.

Application filed July 17, 1917. Serial No. 181,181. Term of patent 14 years.

To all whom it may concern:

Be it known that I, HENRY C. ANDERSON, a citizen of the United States, residing at Athens, in the county of Clarke and State of Georgia, have invented a new, original, and ornamental Design for Bottles, as shown in the accompanying drawing.

The figure is an elevational view of a bottle showing my new design.

I claim:

The ornamental design for a bottle, as shown.

HENRY C. ANDERSON.
